(57) **CLAIM**

The ornamental design for a sheet material with surface pattern for use on a sanding or polishing machine, as shown and described.

DESCRIPTION

The patent or application file contains at lease one drawing executed in color. Copies of this patent or application file publication with color drawing(s) will be provided by the Office upon request and payment of the necessary fee.

The sole FIGURE is a top plan view of a sheet material with surface pattern for use on a sanding or polishing machine. The broken lines surrounding the sheet material with surface pattern for use on a sanding or polishing machine indicate the boundary of the claim and form no part thereof.
